W. A. LOCKARD,
RAILWAY TIE AND FASTENER,
APPLICATION FILED JAN. 7, 1915.

1,137,990.

Patented May 4, 1915.

UNITED STATES PATENT OFFICE.

WILLIAM ALONZA LOCKARD, OF PHILADELPHIA, PENNSYLVANIA, ASSIGNOR OF ONE-HALF TO ARTHUR E. STANGE, OF PHILADELPHIA, PENNSYLVANIA.

RAILWAY-TIE AND FASTENER.

1,137,990.

Specification of Letters Patent.

Patented May 4, 1915.

Application filed January 7, 1915. Serial No. 1,038.

To all whom it may concern:

Be it known that I, WILLIAM A. LOCKARD, a citizen of the United States, residing at Philadelphia, in the county of Philadelphia and State of Pennsylvania, have invented certain new and useful Improvements in Railway-Ties and Fasteners; and I do declare the following to be a full, clear, and exact description of the invention, such as 10 will enable others skilled in the art to which it appertains to make and use the same.

My invention relates broadly to improvements in railway ties and fasteners and more particularly to those employing wedges for 15 clamping the rails in position upon the ties.

The main object of the invention is to provide a comparatively simple device of this character with the parts so constructed and arranged, as to allow channel iron ties 20 to be employed, certain parts being so disposed as to effectively brace the upright flanges of these ties to prevent canting thereof.

As is usual with devices of this character, 25 the wedges are equipped with means whereby they may be locked in adjusted position, and a further object of the invention is to so construct this means as to allow it to assist in effecting the clamping action upon the 30 rails.

With the above and minor objects in view, the invention resides in certain novel features of construction and combination herein described and claimed and shown in the 35 drawings wherein:—

Figure 1 is a top plan view of a tie and fastener constructed in accordance with this invention, showing its application to use; Fig. 2 is a longitudinal section as seen along 40 the plane of the line 2—2 of Fig. 1; Fig. 3 is a perspective view of one of the wedges; Fig. 4 is a similar view of one of the bridge plates to be described; Fig. 5 is a vertical transverse section as seen on the line 45 5—5 of Fig. 2; Fig. 6 is a detail longitudinal section showing the application of a modified form of bridge plate; Fig. 7 is a perspective view of this modified detail.

In these drawings, constituting a part of 50 this application, the numeral 1 designates a channel iron railway tie whose side flanges 2 are provided with pairs of obliquely alined notches 3 in their upper edges, a pair of these notches being located at each end of 55 the tie. By reference to the various figures

of the drawings, it will be seen that all of these notches 3 are provided with flat horizontal bottom walls and with undercut downwardly diverging end walls, this structure being preferable for reasons to be set forth.

Extending transversely from the notches 3 in one flange 2 to those in the opposite flange, is a pair of bridge plates 4 whose ends are bent downwardly into contact with the outer sides of the flanges 2 as seen at 5 in Figs. 4 and 5. These plates form supports for the rails R which rest upon their intermediate portions as shown in Figs. 2 and 6, rail clamping wedges 10 being then 70 inserted between the rails and the undercut end walls of the notches 3. These wedges rest upon the bridge plates 4 and have downwardly diverging outer edges which contact closely with the undercut end walls, 75 while their inner edges lie parallel to each other and are shaped to abut the bases of the rails as shown.

By employing the construction so far described, when the wedges 10 are driven forcibly into place, they not only grip the rails R and hold the same against any possible shifting, but they tend to reinforce the side flanges 2 to prevent them from tilting laterally in respect to the base of the tie, this 80 being due to the fact that the upper ends of the end walls of the notches 3 overlie the inclined outer edges of the wedges, and in order for such tilting of the flanges to take place, it would be necessary for these upper 85 ends of the end walls to move downwardly. It will be obvious, however, that such downward movement is impossible and that the side flanges 2 are therefore effectively reinforced, it being therefore possible to use 90 lighter material than has heretofore been employed for such purposes.

In order to relieve unnecessary strain from the end walls of the notches 3, and to retain the central portions of the wedges 10 in 100 binding contact with the rails, said wedges are equipped with additional wedging means, these means being here shown in the form of bolts 20 and slots 25, the latter being formed longitudinally of the wedges 10 105 and lying parallel to their outer edges, while the former rise through the bridge plate 4 and through said slots, their upper ends being equipped with clamping nuts 30. By this means, when the wedges are driven into 110

place, their end portions are forced against the rails by the end walls of the notches 3, while their central portions are likewise forced into contact with the rails, this being due to the fact that the inner walls of the slots contact with the inner sides of the bolts, said inner sides of said slots thereby constituting supplemental wedging faces at the centers of the wedges 10. This is likewise an important feature of the invention for obvious reasons, and furthermore, because the bolts 20 likewise act as means for clamping the wedges 10 against movement when the nuts 30 are tightened thereon.

In Figs. 6 and 7, a slightly different form of bridge plate 4' is shown which, in addition to the downturned end flanges 5', is provided with side flanges 5'' which rise from the side edges of said plate and converge upwardly, these side flanges contacting with the downwardly diverging outer edges of the wedges 10 and constituting still other wedging surfaces.

From the foregoing description, taken in connection with the accompanying drawings, it will be seen that a comparatively simple tie and fastener has been provided, yet that the device will be very efficient in operation and may be easily and inexpensively manufactured.

I claim:

1. The combination with a railway tie having means to abut one side of a rail, and a pair of shoulders spaced from each other longitudinally of the rail and spaced unequal distances from the other side of the

latter, of a longitudinally disposed wedge interposed between said shoulders and the rail, a supplemental wedge carried by the central portion of the first named wedge and located between the two shoulders, and a rigid projection disposed in contact with the outer edge of the supplemental wedge.

2. The combination with a railway tie having means to abut one side of a rail, and a pair of shoulders spaced from each other longitudinally of the rail and spaced unequal distances from the other side of the latter, of a longitudinally disposed wedge interposed between said shoulders and the rail, and having a longitudinal slot lying parallel to and disposed near its outer edge, and a projection rising from the tie into said slot.

3. The combination with a railway tie having means to abut one side of a rail, and a pair of shoulders spaced from each other longitudinally of the rail and spaced unequal distances from the other side of the latter, of a longitudinally disposed wedge interposed between said shoulders and the rail, said wedge having a longitudinal slot lying parallel to and disposed near its outer edge, a rigid bolt rising from the tie through the slot, and a clamping nut on said bolt.

In testimony whereof I have hereunto set my hand in presence of two subscribing witnesses.

WILLIAM ALONZA LOCKARD.

Witnesses:

ARTHUR E. STANGE,
JOHN DUNN.
